UNITED STATES PATENT OFFICE.

JUSTUS JESSE SMITH, OF NEW YORK, N. Y.

ADJUSTABLE DOOR-JAMB.

1,046,666.

Specification of Letters Patent. Patented Dec. 10, 1912.

Application filed October 4, 1910. Serial No. 535,301.

To all whom it may concern:

Be it known that I, JUSTUS J. SMITH, a citizen of the United States, residing at New York, in the county of New York and State of New York, have invented certain new and useful Improvements in Adjustable Door-Jams; and I do hereby declare the following to be a full, clear, and exact description of the invention, such as will enable others skilled in the art to which it appertains to make and use the same.

My present invention relates to improvements in adjustable door jams, and it consists in providing two members, each made of rolled sheet metal, which may be adjustably connected together and may be quickly and accurately fitted to any door frame, partition block or the like.

My invention will be understood by reference to the accompanying drawing, in which—

Figure 1 is a perspective view, partly in section, showing the edge of the door and a section through the wall adjacent to the door. Fig. 2 shows a horizontal section through the part shown in Fig. 1, but on a larger scale, and Figs. 3 and 4 are details showing the two members, which are adjustably connected together, as shown in Figs. 1 and 2.

Referring more particularly to the drawings, A designates the partition block or wall, and B the door, and with which are associated the two members of the device forming the basis of the present invention. One of said members consists of a rolled metal plate having a portion D, and a narrow portion x disposed parallel to the portion D or body of the plate. Said member D is also provided with an angular section d disposed at right angles thereto and adapted to form an abutment or stop for engaging with the door. A flange d' connects with the portion d, and is disposed parallel with the portions D and x; and which is perforated as shown in Fig. 3 to connect with the other member of the device, as indicated. The portion x has a right angularly disposed extension or flange d² through the medium of which the device is secured to the partition block A. The second member consists of a relatively broad portion E' having a connected portion y disposed parallel therewith; and said portion y has a right angularly disposed flange e' for securing the same to the wall or partition block A.

The broad portion E' is provided with a plurality of elongated slots e to receive the rivets that are carried by the portion d' of the first member, and through the medium, 60 of which the two devices may be adjusted to fit partition blocks or walls of different widths, as will be understood.

For purposes of ornamentation, and also to avoid angular edges, which are objectionable in a door way, the two members D and E may be round or curved, as shown at d² and e² respectively, or other artistic configurations may be adopted if desired.

In order to fit the device to the partition block, it is only necessary to place the two strips so that the flanges e' and d² will bear against the partition block while the member E' is flat against the edge of the same, then mark on the flat portion E' of the member E the position of the edge of the face d, then take the two parts down, rivet them together in the relative position just indicated, put up again, slip the flanges e' d² back until the flat portion E' fits snugly against the 80 face of the partition block and insert the screws F, and the door jamb will be held permanently in place.

If desired, plaster H, molding or the like, may be put on to hide the flanges e' d², as 85 shown in Figs. 1 and 2.

It will be evident that this device may be quickly and accurately fitted to any partition block, door frame or the like, and thus the necessity for accurately finishing the 90 metal parts, which is found difficult and expensive in practice, is almost entirely obviated.

It is desirable in apparatus of this kind to manufacture and sell standard parts, and 95 to apply these parts so manufactured without material changes or expensive machining to various thicknesses of partition blocks, door frames or the like, and this is accomplished by the herein described construction in a cheap, simple, efficient, and at the same time artistic way.

Having thus described my invention, what I claim and desire to secure by Letters Patent in the United States is:—

An adjustable door jamb, consisting of two plates of sheet metal, each provided with a broad and narrow portion disposed in parallel and connected by a curved portion, and each of said narrow portions having a flange disposed at right angles thereto and adapted to engage the side of the parti-

tion block or door frame, the broad portion of one of said members having a flat face adapted to bear against the face of the partition block or door frame, and being provided also with elongated slots transversely disposed, the second member having a vertical face disposed at right angles to said broad portion thereof and adapted to engage the door, and a flange projecting backwardly from said vertical face and in parallel with the broad and narrow portions; and rivets passing through said elongated slots and said

backwardly projecting flange, and clamping the two members together at the desired position, and said curved portions projecting beyond the sides of the doorway, substantially as described.

In testimony whereof, I affix my signature, in presence of two witnesses.

JUSTUS JESSE SMITH.
